U.S. Cl. 424—329

4 Claims

ABSTRACT OF THE DISCLOSURE

A di-(alkoxypropyl)-quaternary ammonium compound is described in which the alkyl groups of the alkoxypropyl radical contain from 8 to 15 carbon atoms. A bactericide having high bactericidal effectiveness in the presence of hard water is also described which includes as its principal bactericidal agent a di-(alkoxypropyl)-quaternary ammonium compound or a mixture of di-(alkoxypropyl)-quaternary ammonium compounds which have alkoxypropyl radicals containing alkyl groups of different chain length, the alkyl groups of different chain length being in the same molecule or in different molecules.

This invention relates generally to quaternary ammonium compositions and more particularly it relates to quaternary ammonium compositions which exhibit high bactericidal effectiveness in the presence of hard water, and to bactericides containing such compositions.

The efficacy of a bactericide may be measured against two types of bacteria, those referred to as gram positive organisms, e.g., *S. aureus*, and those generally referred to as gram negative organisms, e.g., *E. coli* and *S. typhosa*. For many disinfecting uses a bactericide having high bactericidal effectiveness against gram negative organisms is desirable.

The bactericidal activity of quaternary ammonium compounds against both gram positive and gram negative organisms is generally known. Substantially all long chain alkyl quaternary ammonium compounds exhibit some bactericidal activity. Those quaternary ammonium bactericides conventionally employed as bactericides have good bactericidal properties when tested against gram positive bacteria by the standard phenol or AOAC use dilution tests. However, the effectiveness of quaternary ammonium bactericides against gram negative organisms, for example, *E. coli* and *S. typhosa* has not been as good as might be desired, particularly in the presence of hard water.

Quaternary ammonium compounds containing a single long chain alkyl radical having from 8 to 18 carbon atoms and a benzyl radical have generally been considered to have the best bactericidal effectiveness against gram negative organisms. Maximum bactericidal effectiveness of known quaternary ammonium bactericides is achieved when the monoalkyl radical is a mixture of dodecyl (C₁₂), tetradecyl (C₁₄), hexadecyl (C₁₆), and octadecyl (C₁₈) radicals. Alkyl radicals of lesser chain length have been found to have lower bactericidal effectiveness. The bactericidal effectiveness of dialkyl benzyl quaternary ammonium compounds is likewise substantially less than monoalkyl benzyl quaternary ammonium compounds.

Quaternary ammonium bactericides find many uses as

2

sanitizers, algicides, etc., where they are employed in aqueous systems at relatively low concentrations, e.g., 100 to 1000 p.p.m. Accordingly, a bactericide should have good bactericidal effectiveness in the presence of hard water. The hard water tolerance of a bactericide may be measured by a standard hard water tolerance test, known as the "Chambers" test. The Chambers test is a modification of the Weber-Black test (Journal of the American Public Health Association, 38, 1405 [1948]).

In the Chambers hard water tolerance test a hundred milliliter test solution is prepared consisting of one milliliter of a bacterial inoculum, one milliliter of an aqueous solution of the bactericide to be tested, with the remainder being synthetic hard water. The concentration of bacteria in the inoculum is controlled so that the test solution contains between about 75 million and 125 million bacteria per milliliter.

The percentage of bacteria killed after certain specified intervals of time is measured to determine the tolerance of the bactericide to hard water.

Known long chain monoalkyl diamethyl benzyl quaternary ammonium bactericides generally have Chambers hard water tolerances between about 200 and about 750. Some specific types of quaternary compounds have higher Chambers values, but these compounds are generally more complex and are more difficult to manufacture. Known quaternary ammonium compounds which do not contain benzyl radicals generally have lesser Chambers hard water tolerances and are not generally considered to be effective bactericides.

It is a principal object of the invention to provide an easily prepared quaternary ammonium bactericide which exhibits high bactericidal effectiveness against gram negative organisms, particularly when in the presence of hard water. Another object is to provide a quaternary ammonium compound which has good water solubility. A further object is to provide a mixture of quaternary ammonium compounds having a high Chambers hard water tolerance which do not contain benzyl radicals.

Very generally, the present invention is directed to a quaternary ammonium composition which exhibits improved bactericidal effectiveness, particularly against gram negative organisms in the presence of hard water, and which had good solubility in water. More particularly, the invention is directed to a quaternary ammonium bactericide which includes as its principal bactericidal agent a di-(alkoxypropyl)-quaternary ammonium compound or a mixture of di-(alkoxypropyl)-quaternary ammonium compounds having alkoxypropyl radicals which contain alkyl groups having different chain lengths. The alkoxypropyl radicals containing alkyl groups of different chain length may be in the same molecule or in different molecules.

In certain specific instances the bactericide of the invention may contain only di-(alkoxypropyl)-quaternary compounds which have alkoxypropyl radicals containing alkyl groups of the same chain length. In such instances, the Chambers hard water tolerance is less than that obtained when the quaternary ammonium compounds contain alkoxypropyl radicals having alkyl groups of different chain length. However, the hard water tolerance of the bactericide is comparable to that obtained with known monokyl dimethyl benzyl quaternary ammonium compounds.

The quaternary ammonium compounds of the present invention have the formula:

in which R is a straight or branched chain, saturated or unsaturated alkyl radical of from 8 to 15 carbon atoms, R₃ is a saturated alkyl of 1 to 3 carbon atoms, R₄ is a saturated alkyl radical of 1 to 3 carbon atoms or a benzyl radical and X is a salt forming anion. R₃ and R₄ are preferably methyl radicals. The salt forming anion may be a halogen, alkyl sulfate of from 1 to 4 carbon atoms, citrate, tartrate, sulfamate, nitrate, hydroxide, or any other anionic compound which is soluble in water at intended use levels and does not deleteriously affect the bactericide. In most instances a chloride or methyl sulfate anion is employed.

It has been discovered that a particular group of di-(alkoxypropyl)-quaternary ammonium compounds exhibit surprisingly improved bactericidal effectiveness against gram negative organisms in the presence of hard water. Heretofore, high bactericidal activity against gram negative organisms in hard water could be obtained only with monoalkyl dimethyl benzyl quaternary ammonium compounds. Surprisingly, the quaternary ammonium bactericide of the present invention exhibits high bactericidal effectiveness against gram negative organisms in the presence of hard water regardless of whether the quaternary ammonium compounds contain benzyl groups. In preferred forms of the invention superior hard water tolerances against gram negative organisms are obtained when the quaternary ammonium compounds do not contain benzyl radicals.

It has also been determined that the quaternary ammonium compounds which form the bactericide of the invention should contain two alkoxypropyl radicals in order to provide the desired bactericidal effectiveness against gram negative organisms in hard water systems. Monoalkoxypropyl quaternary ammonium compounds and mixtures of these compounds do not achieve the high bactericidal effectiveness of di-(alkoxypropyl)-quaternary ammonium compounds. Further, the bactericidal effectiveness and solubility of the quaternary ammonium compounds is enhanced by the presence of an ether linkage in the alkyl containing radicals. Similar compounds containing dialkyl radicals, but without an ether linkage, have substantially reduced bactericidal effectiveness against gram negative organisms in the presence of hard water.

Superior bacterial effectiveness against gram negative organisms is obtained when the bactericides contain di-(alkoxypropyl)-quaternary ammonium compounds containing alkyl groups of different chain lengths and do not contain benzyl radicals. Further, it has been determined that best results are obtained when the di-(alkoxypropyl)-quaternary ammonium compound contains alkyl groups of different chain lengths in the same molecule.

Alkyl groups of different chain lengths are obtained in the same molecule when the quaternary ammonium compound is prepared from alkyl alcohol raw materials which are a mixture of different chain length alcohols. For example, if the alcohol raw material is a 60 percent-40 percent mixture of n-octyl (C₈) and n-decyl (C₁₀) alcohols, the quaternary ammonium compound formed from the mixed alcohol raw materials will contain some molecules having two octyloxypropyl radicals, some molecules having two decyloxypropyl radicals, and some molecules having one octyloxypropyl radical and one decyloxypropyl radical.

The di-(alkoxypropyl)-quaternary ammonium compounds which form the bactericide may be prepared in accordance with standard techniques. One example of such a process includes reacting an alkyl alcohol which may contain mixed alkyl chains with acrylonitrile fol-

lowed by subsequent hydrogenation of the resulting ether nitrile and finally quaternizing with an alkyl halide or dialkyl sulfate. More specifically, a preferred preparation consists of charging to a reaction vessel an amount of an alkyl alcohol or mixed alkyl alcohols equivalent to about nine moles of the alcohol and about 0.1 percent potassium hydroxide based on the weight of the alcohol. About 20 mole percent excess of acrylonitrile, based on the alcohol or mixture of alcohols, is added slowly to the reaction vessel while the reaction mixture is maintained from 25-35° C. The reaction is completed within 5 to 7 hours. The mixture is then neutralized with glacial acetic acid equal to 1.1 times the chemical equivalent of the quantity of potassium hydroxide, solid residue is removed by then filtering, and excess acrylonitrile is vacuum distilled off, leaving an alkoxypropyl nitrile product.

An amount of the alkoxypropyl nitrile product equivalent to between 3.5 and 4.0 moles is then charged to a reaction vessel, equipped to withstand pressures of 1000 p.s.i.g., along with about 10 g. of Raney nickel. The reactor is then pressurized to about 25 p.s.i.g. with hydrogen and heated to between 300° F and 350° F. When the hydrogenation reaction is initiated the temperature is held at about 400° F. and the hydrogen pressure increased to 150 p.s.i.g. The hydrogen is continually circulated and washed to remove any undesirable gases, such as ammonia, during the course of the reaction. The duration of the hydrogenation reaction is between 1 and 3 hours after which the catalyst is removed leaving a di-(alkoxypropyl)-amine product.

An amount of di-(alkoxypropyl) amine equivalent to about 0.5 mole is then charged to a reaction vessel equipped to withstand pressure up to 500 p.s.i.g. along with 190 grams of isopropanol, 10 grams of water and about 1.25 moles of sodium bicarbonate. The reaction vessel is sparged with nitrogen to remove air, and methyl chloride is added until the pressure inside the vessel reaches 50-70 p.s.i.g. The vessel is then heated to a temperature between 70° C. and 90° C. The reaction mixture is agitated slightly and the reaction is completed in 3 to 5 hours. Periodic venting of the reaction mixture to remove carbon dioxide is advantageous, followed by addition of methyl chloride until a pressure of between 50 to 70 p.s.i.g. is obtained. The reaction is considered complete when the free amine value is between 1.5-0.5. Solid residue is removed by filtering. The soluble reaction mixture remaining consists essentially of di-(alkoxypropyl) dimethyl ammonium chlorides.

It is apparent that other processes and modifications are possible to prepare the di-(alkoxypropyl)-quaternary ammonium compounds which form the bactericide of the invention, and applicant does not intend to be limited to the described method.

The surprisingly good bactericidal effectiveness of a bactericide of the invention can be demonstrated by the Chambers hard water tolerance test. In the Chambers hard water tolerance test described herein, 100 milliliters of test solution was employed. The test solution consisted of 1 milliliter of an inoculum containing *E. coli* USPHS No. 198, Strain ATCC No. 11229, containing sufficient bacteria to provide between about 75 million and 125 million bacteria per milliliter of test solution at the start of the test, one milliliter of the bactericide to be tested in an amount to give 200 parts per million of bactericide in the test solution. The remainder of the test solution was a synthetic hard water having a controlled hardness equivalent to a stated number of parts per million, calculated as calcium carbonate. In each instance herein which a hard water tolerance is set forth, the kill of *E. coli* is at least 99.999 percent within 30 seconds, based upon a concentration of bactericide of 200 parts per million of active ingredients.

Using a Chamber hard water tolerance test as set forth above, the following results were obtained in testing monoalkyl dimethyl benzyl quaternary ammonium

bactericides available in commerce, dialkyl dimethyl quaternary ammonium compounds, and monoalkoxypropyl trimethyl quaternary ammonium compounds.

TABLE I

Example	Composition	Chambers hard water tolerance
1.	n-Alkyl dimethyl benzyl ammonium chloride. ¹	750
2.	do ²	550
3.	Dialkyl dimethyl ammonium chloride. ³	300
4.	Alkoxypropyl trimethyl ammonium chloride. ⁴	<50

¹ 1:1 mixture of 5% C₁₂, 60% C₁₄, 30% C₁₆, 5% C₁₈, and 50% C₁₂, 30% C₁₄, 17% C₁₆, 3% C₁₈ n-alkyl dimethyl ammonium chlorides.

² 40% C₁₂, 50% C₁₄, 10% C₁₆ n-alkyl dimethyl benzyl ammonium chlorides.

³ 60/40 mixture of C₈, C₁₀ n-dialkyl dimethyl ammonium chlorides.

⁴ 60/40 mixture of C₈, C₁₀ n-alkoxypropyl trimethyl ammonium chlorides.

It can be seen from Table I that the Chambers hard water tolerance of known monoalkyl dimethyl benzyl quaternary compounds is better than dialkyl dimethyl quaternary compounds or alkoxypropyl trimethyl quaternary ammonium compounds.

Table II sets forth the Chambers hard water tolerance of various di-(alkoxypropyl)-dimethyl quaternary ammonium chloride compounds in which the alkoxypropyl radicals of each contain alkyl groups of the same chain length.

TABLE II

Example	Composition	Chambers hard water tolerance
5.	[(C ₈ H ₁₅ O(CH ₂) ₃) ₂ N(CH ₃) ₂] ⁺ Cl ⁻	<50
6.	[(C ₈ H ₁₇ O(CH ₂) ₃) ₂ N(CH ₃) ₂] ⁺ Cl ⁻	450
7.	[(C ₁₀ H ₂₁ O(CH ₂) ₃) ₂ N(CH ₃) ₂] ⁺ Cl ⁻	400
8.	[(C ₁₂ H ₂₅ O(CH ₂) ₃) ₂ N(CH ₃) ₂] ⁺ Cl ⁻	100

It will be seen that di-(alkoxypropyl) dimethyl ammonium chlorides containing 8 or 10 carbon atoms in the alkyl group show a much improved Chambers hard water tolerance as compared to similar compounds containing 6 or 12 carbon atoms in the alkyl group. Further, these compounds have about as good hard water tolerance as do the monoalkyl dimethyl benzyl compounds of Table I, and are considered to be effective bactericidal agents for use in water systems.

In accordance with the preferred form of the invention, the di-(alkoxypropyl)-quaternary ammonium compounds are prepared from a mixture of alkyl alcohols of different chain lengths in order that the quaternary ammonium product will comprise a mixture of different compounds containing, for example, molecules having two C₈ alkyl groups, molecules having two C₁₀ alkyl groups, and molecules having one C₈ alkyl group, and one C₁₀ alkyl group. When mixed alkyl alcohol raw materials are employed, it has been determined that at least about 30 percent, and usually about 45 percent, of the di-(alkoxypropyl)-quaternary ammonium product will be of the type which has alkoxypropyl radicals having alkyl groups of different chain lengths on the same molecule.

Surprisingly improved Chambers hard water tolerances are obtained when these quaternary ammonium products are employed as bactericides. Table III illustrates results obtained when mixtures of n-alkyl alcohols were employed as raw materials to prepare mixtures of di-(alkoxypropyl)-dimethyl ammonium chlo-

rides. In each example a 60/40 weight percent mixture of alcohol was used:

TABLE III

Example	Alcohol raw material	Chambers hard water tolerance
9.	60% C ₈ -40% C ₈	<50
10.	60% C ₈ -40% C ₁₀	75
11.	60% C ₈ -40% C ₁₂	200
12.	60% C ₈ -40% C ₁₀	900
13.	60% C ₈ -40% C ₁₂	600
14.	60% C ₁₀ -40% C ₁₂	400
15.	C ₁₂ -C ₁₅ ¹	300

¹ Cut of petroleum alcohols, which also contains C₁₃ and C₁₄ alcohols, having approximately a 3:2 ratio of C₁₂:C₁₅.

Examination of Table III clearly indicates that unexpected bactericidal effectiveness is obtained when the alkyl groups of the alkoxypropyl radicals contain from 8 to 15 carbon atoms. Further, a substantial improvement in bactericidal effectiveness is obtained when using a mixture of n-alkyl C₈-C₁₀ and C₈-C₁₂ alcohol raw materials as compared to similar compounds (Table II) in which the alcohol raw material was a n-alkyl alcohol of a single chain length.

To determine optimum ratios of the alcohol raw materials C₈-C₁₀ di-(alkoxypropyl)-dimethyl ammonium chlorides were prepared from different ratios of alcohols. The results are set forth in Table IV.

TABLE IV

Example	Alcohol raw material	Chambers hard water tolerance
16.	100% C ₈	450
17.	80% C ₈ -20% C ₁₀	850
18.	60% C ₈ -40% C ₁₀	900
19.	40% C ₈ -60% C ₁₀	850
20.	20% C ₈ -80% C ₁₀	750
21.	100% C ₁₀	400

Table IV clearly illustrates that an alcohol raw material mixture of between about 20 percent and about 80 percent by weight n-octyl alcohol, and between about 80 percent and about 20 percent n-decyl alcohol results in a di-(alkoxypropyl)-quaternary ammonium product of improved bactericidal effectiveness. Best results are obtained when the alcohol raw material is a mixture of about 60 percent n-octyl alcohol and about 40 percent n-decyl.

In addition to the improved bactericidal effectiveness obtained when the quaternary ammonium compounds are prepared from mixed alcohol raw materials, it has also been determined that improved bactericidal effectiveness is obtained when di-(alkoxypropyl)-quaternary ammonium compounds prepared from single alcohol raw materials (i.e., when both alkoxypropyl radicals of the molecule have alkyl groups of the same chain length) are mixed together after preparation. Table V illustrates results obtained utilizing various physical mixtures of di-(octyloxypropyl)-dimethyl ammonium chloride and di-(decyloxypropyl)-dimethyl ammonium chloride.

TABLE V

Example	Ratio of dioctyl to didecyl ammonium chloride	Chambers hard water tolerance
22.	100 di C ₈	450
23.	80% di C ₈ -20% di C ₁₀	750
24.	60% di C ₈ -40% di C ₁₀	750
25.	40% di C ₈ -60% di C ₁₀	750
26.	20% di C ₈ -80% di C ₁₀	600
27.	100% di C ₁₀	400

Table V indicates that mixtures of di-(alkoxypropyl)-quaternary ammonium prepared from single n-alkyl alcohol raw materials provides improved bactericidal effectiveness as compared to the compounds singularly,

and that this improvement is significant when the mixture of compounds contains between about 80% and about 20% of one quaternary ammonium compound, and between about 20% and about 80% of the other quaternary ammonium compound.

Di-(alkoxypropyl)-quaternary ammonium compounds in which one methyl radical is replaced by a benzyl radical also exhibit bactericidal effectiveness, although somewhat lesser than similar compounds which do not contain a benzyl radical. A C₈, C₁₀ di-(alkoxypropyl)-methyl benzyl quaternary ammonium compound, prepared from a 60/40 mixture of n-octyl and n-decyl alcohol raw materials has a Chambers hard water tolerance of about 500. This is comparable to the Chambers' hard water tolerance of conventional monoalkyl dimethyl benzyl quaternary ammonium compounds of the type described in Table I, and di-(alkoxypropyl)-methyl benzyl quaternary ammonium compounds are considered to be useful bactericides. However, their bactericidal effectiveness is not as good as similar compounds which do not contain benzyl radicals (Table III).

Bactericides containing the described quaternary ammonium compounds as their principal active agent are useful as sanitizers, algicides and as additives to feed water for poultry. The bactericides may be used by themselves or in admixture with various nonionic detergents and builders. A bactericide incorporating the compositions of the invention may be prepared by preparing a mixture of 50 percent by weight of the di-(alkoxypropyl)-quaternary ammonium compound, 15 percent by weight isopropanol, or other lower alkyl alcohol, and 35 percent by weight of water. Of course other formulations are also contemplated.

It can be seen that a novel quaternary ammonium composition has been described. The quaternary ammonium composition has unusually high bactericidal effectiveness in the presence of hard water. Although certain features of the invention have been set forth with particularity in order to accurately describe the invention, alternative embodiments within the skill of the art are contemplated. 35 40

Various of the features of the invention are set forth in the following claims.

What is claimed is:

1. A quaternary ammonium bactericide of high bactericide of high bactericidal effectiveness which includes

as its principal bactericidal agent a mixture comprising a compound of the formula

and a compound of the formula

where R_1 and R_2 are straight or branched chain, saturated or unsaturated alkyl of from 8 to 15 carbon atoms, R_3 is saturated alkyl of 1 to 3 carbon atoms, R_4 is saturated alkyl of 1 to 3 carbon atoms or benzyl, X is a water soluble salt forming anion, and R_1 and R_2 are different, and whereby the bactericidal effectiveness of the mixture as tested in hard water is greater than the effectiveness of either component of the mixture alone.

2. A quaternary ammonium bactericide in accordance with claim 1 which in addition includes a compound of the formula

where R_1 and R_2 are straight or branched chain, saturated or unsaturated alkyl of from 8 to 15 carbon atoms, R_3 is saturated alkyl of 1 to 3 carbon atoms, R_4 is saturated alkyl of 1 to 3 carbon atoms or benzyl, X is a water soluble salt forming anion, and R_1 and R_2 are different.

3. A quaternary ammonium bactericide in accordance with claim 2 wherein R_3 and R_4 are methyl and X is chloride.

4. A quaternary ammonium bactericide in accordance with claim 3 where R_1 is n-octyl and R_2 is n-decyl.
